UNITED STATES PATENT OFFICE.

THOMAS C. KENNEDY, OF CHICAGO, ILLINOIS.

COAL-HANDLING APPARATUS.

1,293,466.

Specification of Letters Patent.

Patented Feb. 4, 1919.

Application filed August 14, 1916. Serial No. 114,254

To all whom it may concern:

Be it known that I, THOMAS C. KENNEDY, a citizen of the United States, residing at Chicago, in the county of Cook and State of Illinois, have invented certain new and useful Improvements in Coal-Handling Apparatus, of which the following is a specification.

My invention relates to improvements in conveying apparatus.

One of the objects of my invention is to provide, in a system of conveying mechanism, means for conveying material in bulk from the bottom of a supply within a container, without having to overcome the resistance to movement of the conveyer imposed by the weight of the superposed mass.

Another object of my invention is to generally improve devices of this character, Other and further objects of my invention will become readily apparent, to persons skilled in the art, from a consideration of the following description when taken in conjunction with the drawings, wherein:

Figure 1 is an elevation of a coal storage plant, showing parts in section, into which coal may be deposited by my improved conveyer.

Fig. 2 is an enlarged broken-away section of the receiving hopper showing the conveyer in connection therewith.

Fig. 3 is a section taken on line 3—3 of Fig. 2.

In all the views the same reference characters are employed to indicate similar parts. While my invention may be used for conveyers in general in many and various environments for conveying or handling all sorts of materials, such as coal, sand, broken stone and other like substances in bulk, without departing from the spirit and scope of the appended claims, I will, for purposes of disclosure, describe its use in a coal handling system, illustrated by the accompanying drawings.

In transferring or unloading and loading coal, or other similar material, from one car to another, in accordance with modern practice, as therein illustrated, it is first dumped into a hopper, or other similar suitable receiving bunker, from which it is taken by a conveyer to an elevator which raises and dumps it into another similar hopper or receptacle located at a higher altitude and from which latter depository the coal is caused to flow by effect of gravity, into an

other car or other conveyer which may be located in substantially the same horizontal plane as the car from which it was initially or primarily taken. The parts of the apparatus which conveys the coal from the lower to the higher bunker or depository, are cooperatively timed and automatically controlled. By this means the apparatus will continue to operate, without requiring manual supervision or attention, until all of the coal has been transferred from the lower hopper to the higher hopper. Such a system of coal storage is especially convenient as a means for storing and supplying of coal and the delivering of same at intervals in admeasured quantities to railway cars, locomotives, tipple screens or the like.

One of the difficulties to be encountered, in such a system of handling coal or such other material in bulk, is the almost insurmountable obstacle interposed by the weight of the superposed material upon the conveying means that must, of necessity, take it from the bottom of the deposited mass.

My present invention is especially concerned with this feature of such a system. In the accompanying drawings in which I have illustrated only one exemplification of the use of my invention, 10 is a building structure provided with a coal hopper, bunker or depository 11, having an angularly tapering floor 12 and provided with a vertical addition, or cupola 13, into which an elevator for lifting the coal, may be extended. Within the building, and below the bin or bunker 11, is a passage way 14, the lower portion of which 15, constitutes a receptacle or hopper for receiving the coal which may be dumped therein, from the car 16. A pit contains the operative part of the coal conveyer, for conveying the coal from the hopper 15 into an elevator bucket 19, which latter is also located in the pit 17. 20—20 are the vertical guide-ways for the elevator bucket 19, and 21 is the lifting rope or cable for raising the bucket and which is secured thereto, as at 22. 23 is the winding drum and other machinery for operating the conveyer 18 and for lifting the elevator bucket 19.

It will be observed that the bottom walls 15' of the hopper or bin 15, taper inwardly to a central opening 25 and that under this opening the operative conveyer flight 18 is located. Standards 26—26 are spaced apart and rest on the floor 17' of the pit 17 and

provide bearings for the shaft 27. Spaced apart sprocket wheels 28 are carried on the shaft 27, and afford supports for the conveyer chain strands 30, respectively. A 5 plate 31 constitutes the bottom of the conveyer and extends from the front upper and downwardly and rearwardly, as at 32, to a point substantially in the same horizontal plane as the shaft 27. The plate 31 is supported by the angle bars 33-33 and these angle bars are held in place by vertical posts 34 and 35. A transversely extending shaft 37, on the upper front end of the conveyer 18, carries the driving sprocket wheels 38-38 10 for the chains 30-30 of the conveyer. These sprocket wheels are held in spaced relation on the shaft 37.

Vertically disposed plates 40, one on each side of the conveyer, extends from the shaft 27 to the upper front end and surround the shaft 37 and provide bearings 41 therefor.

These plates 40 are provided with openings 42 which coincide with the openings 25 in the bottom of the hopper. The plates 25 40 are properly spaced and held apart by the stationary drums or spools 43 which surround the shafts 27 and 37 respectively.

The shaft 37 carries a driving pulley 45 for a driving chain 46 that is driven by the 30 mechanism 23. Erected on the front of the conveyer is a strengthening frame 48 consisting of the vertical posts 49-49 and 50-50, and the cross bars 51 and 52; which are connected to relatively short bars 53-53 35 that are parallel with the angle bars 33. This frame is also connected to the vertical plates 40 and serves as means for strengthening the front of the conveyer.

Suitably supported upon the side walls 40 15' of the bin or hopper 15 and immediately over the conveyer 18 is an arched canopy 55, sufficiently wide at its lower end to include the upper portion of the conveyer chain strands 30-30 between its vertical 45 walls, and arched at the upper portion, as at 56, in order to withstand the heavy weight of the coal 60 that may be imposed thereon. The conveyer, as illustrated, carries only two flights or drags 57 and 58 50 so arranged that when the flight has been moved up to a given position the other flight will have been moved to the position occupied by first mentioned flight. The coal in the bin 15 will move by gravity through 55 the openings 42-42 in the plates 40-40 and be deposited upon the floor 31 of the conveyer 18. The flight 57, of the conveyer, will carry forward the coal that has been deposited in front of it upon the floor 31 60 to the hinged apron 63, and the only material friction imposed upon the conveyer results from contact of the bottom portion of the chain with the surrounding coal, the upper portion of the chain being guided 65 and protected by the arched canopy or con-

veyer guard 55, so that the conveyer chains may move freely upon their return to the lower or rear sprocket wheels 28-28.

The apron 63 is pivoted, as at 64, and is held in its highest position, shown in Fig. 70 2, by the counter weight 65. When the bucket returns to the pit, it engages and pulls down this apron into position shown in dotted lines in Fig. 6, so as to more conveniently deposit the coal in the vertically 75 movable bucket 19. After the coal has all fallen from the apron 63 into the bucket 19 the counter weight 65 will once more bring the apron into the position shown in Fig. 2, thereby removing it from the path of 80 the vertically movable bucket 19 until the bucket returns to its pit on down trip.

The arrangement of operation is such that the conveyer 18 may stand still while the bucket 19 is being conveyed to the top 85 into the tower 13 and there inverted so as to deposit the coal in the bin 11 and is returned to its lowest position. When the bucket 19 returns to the position shown in Fig. 1, the conveyer 18 is thereupon automatically started or it has moved continuously so to have just enough material ready for bucket to receive it when the bucket is below apron 63 and the amount of coal that it will deliver into the bucket, during 90 one-half revolution of the conveyer chains, is sufficient to fill the bucket, after which the bucket will once more start on its upward journey, being set into operation by suitable automatically operable means, 95 100 which is not any part of the subject matter of this invention.

The locomotives 70 and 71 may be placed upon the tracks 72 and 73, respectively, as shown in Fig. 1, and coal may be taken from 105 the bin or depository 11 through the respective chute 75 by pulling upon the ropes that control the valve to permit the coal to pass through the chute.

While I have herein shown a single embodiment of my invention for the purpose of clear disclosure it is manifest that many changes may be made in the general construction and arrangements of the parts within the spirit and scope of the appended 110 claim, and furthermore my conveyer guard may be used in connection with conveyers that feed a constant stream of any material in bulk from one receptacle to another, and is not limited in its use to conveying coal. 115

Having described my invention, what I 120 claim is:—

In a conveyer system, the combination of a receiving bin; a conveyer flight passing through the bin near the bottom thereof, 125 said flight elevated at its discharge end above its receiving end; a guard over said flight within the bin, having openings in its side walls to admit material to be conveyed to the conveyer; an elevator bucket 130

for receiving a charge from said conveyer and elevating it, and constantly moving automatically operable means for alternately moving said conveyer and bucket whereby the bucket will be raised and lowered between each time of operation of the conveyer.

In testimony whereof I hereunto set my hand in the presence of two subscribing witnesses.

THOMAS C. KENNEDY.

In the presence of—

JOHN W. PADDICK,
A. G. DOUGLASS.
